UNITED STATES PATENT OFFICE

JOSEPH SNIDER, OF VANCOUVER, BRITISH COLUMBIA, CANADA

DOMESTIC CONTINUOUS IRONING DEVICE

Application filed April 29, 1929, Serial No. 358,927, and in Canada April 2, 1929.

This invention relates to a domestic ironing device of rotatable type and more particularly adapted for the ironing of larger domestic articles such as sheets, table-cloths and 5 the like.

Its object is to provide a device of this character by which the arduous labour which attends the ironing of these large-sized articles when an ordinary hand or flat iron is 10 used may be in large part eliminated without recourse to the usual expensive ironing machine.

Further objects are that the rapid increase in the use of domestic washing machines demands a corresponding advantage in regard 15 to the finishing processes of laundering which has not hitherto been available: And moreover my invention meets this need by utilizing heat energy which is otherwise 20 usually wasted and is available in locations where neither gas nor electric power is available.

In effecting these objects I make use of the ordinary kitchen cooking range to provide 25 the hot smoothing surface against which the clothes to be ironed are revolvably pressed by simple mechanism. In this way an effective ironing machine is made available to the average householder at a fraction 30 of the usual cost of same.

By making the external end surface of a range concave lengthwise of and adjacent the fire-box, and providing a cylindrical member adapted to revolve within the concavity, 35 I have the two essential elements of an ironing machine. The former is integral with the range either as originally made or by attachment thereto and is provided with a cylindrically true and smooth concave surface. The latter member is mounted on a 40 simple framework in which it may be revolved by hand, foot treadle, or electric motor as desired.

The front end of the revolvable cylinder is 45 free from bearing or other obstruction on the range side, so that certain articles of clothing may be passed over the end of the device without undesired crushing or creasing.

50 The device is more clearly described in de-

tail by the aid of the drawings herewith and forming a part of this application and in which:

Figure 1 is a front elevation of a kitchen range with the ironing device shown in position at the end thereof. 55

Figure 2 is an end view of the same range and a side view of the device.

Figure 3 is a vertical cross section on line 3—3 of Figure 2. 60

In these drawings the numeral 4 indicates an ordinary kitchen cooking range, and 5 the concave portion arranged horizontally along one end. The external curved surface of the concavity is preferably ground true 65 and afterwards nickel-plated and on the inner or fire-box side may have a filler member for heat conservation and conduction purposes. 70

The revolvable ironing cylinder is shown at 6. This has an external covering of textile fabric as usual and its spindle 7 is carried in the end standard 8 at one end and by the extremity of the long bracket bar 9 at the other. 75

A simple form of treadle 10 is indicated as one means of rotating the roller 6, but whenever possible an electric motor is to be preferred. The drawings indicate a pitman rod 11 actuating a crank pin on the driving pinion 12 from which, by the driving band 13 engaging the pulley 14, the rotation of the ironing cylinder is secured. 80

The standard 8 is pivoted at 15 and is held in engagement with the end of the range by the extension spring 16 in order that the necessary adjustment required for fabrics of differing thickness may be available. 85

If for any reason the revolvable cylinder 6 requires to be quickly released from action this is effected by the lever 17 which fulcrums on the spindle 7 and by the engagement of its short arm against the pin 18 forces back the spindle 7 in the slot 19 and against the spring 20, thus withdrawing the cylinder 6 from contact with the concavity 5 so that fabrics being ironed may be released or adjusted. It is to be noted that the front end of the bracket bar 9 is secured to the range by the hook device 21. 90

The device is operated as follows: After 100

the smooth convex surface 5 has been heated by the range to the required temperature, the fabrics to be ironed are passed inwardly of the range over the top of the cylinder 6 at 22 5 so as to emerge at 23 when the latter is revolved. Motion is then given to the cylinder 6 by a hand crank at 24 or by foot pressure on the treadle 10, or by electric motor as desired. Should the fabrics jam or become unsuitably 10 creased, the lever 17 is depressed, thereby forcing back the cylinder 6 from the surface of the concavity 5 and against the action of the spring 16 when the fabrics are releasable from the cylinder.

15 Having now particularly described my invention, what I claim and desire to be protected in by Letters Patent, is:

1. In combination with a domestic cooking range, an external smooth-surfaced arcuate concavity integral with the fire-box side of said range and adapted to correspond with the surface of a cylindrical member extending horizontally across the end of said range, a cylindrical roller member adapted to be revolvable in said arcuate concavity, a framework positioned adjacent the end of said range and adapted to pivotally support said roller whereby the latter may be swung away from contact with said concavity or drawn 25 into contact therewith, means for suitably revolving said roller.

2. In combination with a domestic cooking range, an external smooth-surfaced arcuate concavity integral with the fire-box side of 35 said range and adapted to correspond with the surface of a cylindrical member extending horizontally across the end of said range, a cylindrical roller member adapted to be revolvable in said arcuate concavity, a framework positioned adjacent the end of said range and adapted to pivotally support said roller whereby the latter may be swung away from contact with said concavity or drawn 40 into contact therewith, means whereby said roller may be quickly released from contact with said arcuate surface independently of the movement of said framework, said means including a lever of the first order fulcrumed 45 on the spindle of said roller and having its short arm engageable against a stop on said framework whereby said spindle is forced away from said concavity in a slot and against the action of a spring, and means for suitably 50 revolving said roller.

55 In testimony whereof I affix my signature.

JOSEPH SNIDER.
